METHOD AND MEANS FOR TREATING
LIVING TISSUE

Reinhold H. Wappler, Yonkers, and Frederick Charles Wappler, New York, N. Y.; Frederick C. Wappler, executor of said Reinhold H. Wappler, deceased

Application November 3, 1932, Serial No. 640,972

8 Claims. (Cl. 174—89)

Our present invention relates generally to the art of treating living tissue, and has particular reference to a new mode of treatment, coordinately, to a new and improved instrument.

5 It is a general object of our invention to provide a new method of heat treating tissue for the general purpose of alleviating protrusions or abnormal swellings or growths; and it is a particular object of our invention to provide a mode of treatment which is essentially non-surgical and which is largely predicated upon the ability of the body itself, during its natural functioning, to absorb or digest properly devitalized matter.

10 Our present method and instrument involves the employment of high-frequency electric currents of the general character which have recently proven themselves to be remarkably efficacious in producing a variety of effects. For example, a sustained high-frequency current of the character which is produced by an electrical generating apparatus of the general type illustrated and described in the copending application of Frederick Charles Wappler, Serial Number 581,903, is suitable for our present purposes.

15 25 It is well known that the passage of small amounts of high-frequency current through body tissue will produce a pure non-surgical diathermic effect which consists essentially in gently warming the tissue. Such treatment stimulates not only the flow of blood and lymph, but also the general activity of the tissue cells and is a widely accredited mode of treating living tissue for the purpose of producing certain well-recognized therapeutic effects.

20 30 35 Where a greater amount of current is employed, the effect of its passage through living tissue has been found to produce what has come to be known as "coagulation", whereby an actual "cooking" of the tissue is effected, resulting not only in destruction of tissue cells and blood vessels and the like, but also in actual coagulation and dehydration of blood and lymph. This mode of treatment is of a valuable character, for example, in effecting hemostasis, during the performance of surgical operations; and it has also been resorted to, with more or less success, in the alleviation of protrusions and similar masses. Its employment is, however, necessarily accompanied by the production of dead tissue or matter which must be immediately excised, resected, or withdrawn, especially where such masses of dead matter are produced in large quantities. Relatively smaller areas of coagulated areas are readily sloughed by the body, and frequently without any injurious results, but this action is in-

herently dangerous and is akin to actual excision, as distinguished from normal absorption by the body itself.

With still greater quantities of current, a cutting effect is produced which has proven to be of extreme value in the performance of a number of surgical operations. 5

Our present invention is predicated upon the discovery that the employment of a high-frequency current of the character mentioned, in concentrations greater than those which produce pure warming, yet less than those which produce even mild coagulation, has a remarkable and highly important effect upon tissue which is, strangely enough, entirely different and distinct 15 from the well known effects hereinbefore mentioned. The effects produced are somewhat akin to pure diathermy in so far as the flow of blood and lymph are stimulated, but distinctly different from pure warming effects by virtue of the 20 fact that actual shrinkage or recession of matter may be accomplished without resorting to any excision or relying upon sloughing of dead matter. Furthermore, the effects produced are somewhat 25 akin to coagulation in so far as a certain devitalization of cells seems to be accomplished, but the effects are entirely different and distinct from coagulation in that the liquid state of the blood and lymph remains utterly unimpaired.

The present effects first manifest themselves 30 under current concentrations of the order of two milliamperes per square millimeter, and appear to be most advantageously produced at approximately four milliamperes per square millimeter. Ordinary mild coagulation as the same is now 35 practiced in the art is not capable of accomplishment under concentration less than approximately six milliamperes per square millimeter.

The present mode of procedure, and the effects produced thereby, have been termed by us, for 40 lack of a better designation, as "non-destructive shrinkage", and consist apparently in a devitalization of tissue cells sufficient to interrupt and disorganize the normal activities of such cells, coupled with a stimulation of the normal flow 45 of blood and lymph. The importance of this result will be obvious, inasmuch as it is the normal blood and lymph flow which lies at the basis of natural absorption by the body itself. From the standpoint of blood and lymph flow, the present 50 effect is apparently new and valuable because of the fact that the cell activities are not simultaneously stimulated but are, on the contrary, disrupted; and from the standpoint of disorganization and devitalization of cells, the present 55

effect appears to be novel and highly desirable because of the fact that it is not accompanied by any impairment of the natural circulatory systems of blood and lymph which feed the cells in question.

The present effect distinguishes further from ordinary well known coagulation in that the normal coagulative treatment is cumulative in its effect. As more and more tissue becomes coagulated, it becomes more and more non-conductive, and the corresponding increase in resistance produces more and more coagulation and dehydration. The present type of treatment of tissue is not cumulative and is, in this respect, similar to ordinary non-surgical diathermy. The time factor in the present case increases the penetration of the effect at a rate of approximately one-fourth inch per minute, but is not accompanied by any increase in current concentration through the tissue subjected to the treatment.

Apparently the present procedure results from the generation of a heat which is sufficient to devitalize and disorganize cells and cell activities, yet insufficient to impair the normal liquidity of the blood and lymph. This immunity of the latter fluids may perhaps be due to the cooling effect of the latter upon the walls of the vessels and capillaries through which these fluids flow.

The effect of our present mode of treatment lies in a recession or shrinkage of the areas or masses which are subjected to the passage of the current, as hereinbefore described, and most of this shrinkage takes place after the treatment has been completed, as a result of which we have been led to the conclusion that the recession is a normal one, resulting from the natural functioning of the circulatory systems of the body in absorbing or digesting the cells which have been suitably devitalized. The treatment is accompanied by no rise in temperature nor in any other discomfort or undesired reaction.

The instrument which we prefer to employ in carrying out the present procedure is one of relative simplicity and is simple to manufacture, control, and manipulate. It consists essentially of an electrode member which is tubular in character and which is provided with a wall portion adapted to serve as an operative surface for contacting the tissue to be treated. The electrode member is preferably mounted within an endoscopic sheath of an insulating material and has a telescope and illuminating means mounted in its interior. The electrode member is adapted to be rotated with respect to the sheath and the telescope, so that either the operative surface or an opposite sight opening may be selectively positioned in the field of vision of the telescope. Means are provided for constantly subjecting the interior of the electrode member to the cooling action of water or the like, whereby the operative electrode surface is kept in a cool condition and whereby surface dehydration of the tissue being treated is reduced to a minimum.

We achieve the foregoing objects, and such other objects as may hereinafter appear or be pointed out, in the manner illustratively exemplified in the accompanying drawing, wherein—

Figure 1 is a side elevational view of an instrument constructed in accordance with our present invention;

Figure 2 is a similar view, on an enlarged scale, with portions shown in cross-section;

Figure 3 is a view taken from the bottom of Figure 2, showing the operative end of the instrument in one relationship of parts;

Figure 4 is a view similar to Figure 3, showing a different relationship of parts;

Figure 5 is a cross-sectional view taken substantially along the line 5—5 of Figure 2, with certain pieces of mechanism omitted for the sake of clearness; and

Figure 6 is a view similar to Figure 5, with the parts in the relationship shown in Figure 4.

The endoscopic tube or sheath 10 is composed of insulating material, and is laterally fenestrated 10 at its forward end, as at 11. It terminates at its rear end in a collar 12, also preferably of insulating material, and with the receptive rear neck 13 into which the operative portions of the instrument are adapted to be inserted.

Carried by the neck 13 is the irrigation outlet tube 14, as well as the block 15 which serves to facilitate the attachment of the interior elements. The block 15 is preferably provided with a clamping device 16 which may be of any conventional 20 or desired character.

The unit which is adapted to be inserted into the neck 13 consists of the tubular element 17 with a forward attenuated portion 18 adapted to be inserted into a wedged relationship with the neck 13. During this association of parts, the fork 19 is adapted to engage around the block 15, and the clamping device 16 is adapted to contact with or engage one or more pins 20 provided on this fork, in the conventional manner.

At the rear end of the element 17, the latter is 30 interiorly threaded and is adapted to receive the ferrule member 21. This member carries the irrigation inlet conduit 22, the latter communicating with the longitudinally arranged conduit 23 which extends forwardly well into the body of the sheath 10, as will be presently described in greater detail.

The ferrule member 21 also carries the rearwardly extending tubular guide 24 through which 40 a suitable telescope is adapted to be inserted and accommodated, the usual clamping device 25 being preferably arranged at the rear end of the guide 24.

The telescope which we prefer to employ is 45 constructed substantially like that illustrated and described in Letters Patent No. 1,680,491, and consists preferably of an elongated tube having a suitable eyepiece 26 at the rear end, an objective lens 27 near the forward end, and a lamp 28 mounted upon an attenuated forward extension. The objective 27 is adapted to command a forwardly oblique field of vision which is illuminated by the lamp 28, and the electrical connections for the lamp 28 may be made in any convenient 55 and customary manner at the terminal rings 29 provided immediately in front of the eyepiece 26.

The mounting of the telescope is facilitated by providing a small tubular guide 30 near the front end of the conduit 23, this guide 30 being secured to the conduit in any convenient manner and serving to support the forward end of the telescope and hold it in fixed relationship to the conduit 23.

On the interior of the element 17 we provide 65 an annular recess or groove in which a collar 31 is rotatably mounted. The collar carries the radially projecting handle 32 which extends outwardly through an arcuate slot in the element 17. This slot extends through approximately 180° 70 so that the handle 32 may be rotated from the full-line position of Figures 1 and 2 to the dot-and-dash position of Figure 2, and back again, but no further. This permits a rotatability of the collar 31 through approximately 180°. 75

Carried by the collar 31 is the present type of electrode member which is composed of a metallic tube 33 extending forwardly in snug yet rotatable relationship with respect to the sheath 10. It is to be noted that this tube encompasses the conduit 23 and the telescope 24. Accordingly, although the telescope and the conduit 23 are arranged within the tubular electrode member 33, the latter may be rotated with respect to these elements, and with respect to the sheath 10, by virtue of the fact that the telescope and the conduit 23 are secured to the sheath 10 through the intermediary of the ferrule 26 and the element 17.

At the forward end of the electrode member 33, the latter is provided with a closed and rounded end or tip 34 which is of insulating material. This tip extends somewhat beyond the forward end of the sheath 10, so that when the entire assembly is inserted into a body cavity the forward edge of the sheath 10 will not impair the ease with which this may be accomplished.

Slightly to the rear of the tip 34, the electrode member 33 is provided with a wall portion 35 (Figures 4 and 6) which is adapted to serve as an operative surface for establishing contact with the tissue to be treated. This wall portion is preferably provided with the relatively small and narrow slit 36. The opposite wall portion is cut away to provide the relatively large opening 37.

The various parts are so mounted that the rotatability of the tubular member 33 within the sheath 10 permits either the operative surface 35 or the opposite opening 37 to be selectively positioned in registry with the fenestra 11 of the sheath 10. Furthermore, the telescope 24 is so mounted that it constantly commands a field of vision through the fenestra 11. Accordingly, when the tubular electrode member 33 is rotated into the position of Figures 2, 3, and 5, the telescope commands an unobstructed illuminated field of vision through the opening 37 and the fenestra 11. When the member 33 is rotated through 180°, the operative surface 35 is exposed through the fenestra 11, but a certain degree of visibility is still achieved through the slit 36.

In either of the extreme positions of the member 33, the flow of irrigating liquid is unimpeded by virtue of the fact that a pair of openings 38 are arranged in the tube 33, in opposite walls thereof, in alignment with the outlet 14.

All of the parts, except the tip 34, the sheath 10, and the collar 12, may be composed of conductive material and are preferably composed of metal. The element 17 also carries an electric terminal 39 which is thus electrically connected with the tube 33 and hence with the operative surface 35, and which is adapted to be connected to a suitable source of high-frequency current.

When the instrument is employed, it is first inserted into the desired body cavity with the parts in the relationship of Figures 1, 2, 3, and 5. Complete illuminating visibility is thus maintained, until the desired area, usually a protrusion, is properly located and positioned within the fenestra 11. The handle 32 is then rotated through 180°, thereby swinging the member 33 into the relationship of Figures 4 and 6, and thereby positioning the operative surface 35 in direct contact with the area of tissue to be treated. Constant irrigation may be maintained through the inlet 22, thence through the conduit 23, to the operative area, thence rearwardly through the tubular member 33, and out of the outlet 14.

With suitable electrical connection made to the terminal 39, and with a corresponding suit-

able connection between an indifferent electrode and a relatively remote portion of the body being treated, high-frequency electric current may be caused to pass through the tissue area which is contacted by the surface 35. The area may, to a certain degree, be kept under visibility by virtue of the slit 36, although it will be understood that the instrument must be rotated slightly in order to bring into vision the tissue that has been in contact with the surface 35.

The current which we employ has a concentration within the range between approximately two and six milliamperes per square millimeter, and the effect upon the tissue may be accurately foretold, in accordance with the area subjected to the treatment and the time duration of the treatment. Thus, for a desired depth of penetration of the present effect, a known current concentration throughout the known contact area of the operative surface 35 can be definitely caused to produce the desired effect in a calculated and predetermined period of time.

As hereinbefore stated, the treatment is not accompanied by any coagulation or destruction of tissue, as the same is ordinarily recognized or thought of. The surface under treatment usually undergoes a slight blanching in appearance, but there is very little surface dehydration (this is reduced to an absolute minimum by the cooling effect of the irrigation liquid), and there is no cumulative penetration of any coagulating effect. Accordingly, the treatment is not accompanied by the formation of any dead mass which must be excised or which will ultimately be sloughed.

The effects of the treatment, after a period of a day or so, are, however, truly remarkable inasmuch as a substantial recession or shrinkage of the tissue inevitably manifests itself. This, we conclude, is due to a natural absorption by a stimulated blood and lymph circulatory system, of cells which have been sufficiently disorganized and devitalized to permit themselves to be absorbed. This shrinkage or recession is accompanied by a normal degree of recession of capillaries and the like, as in all natural cases of absorption.

While our method and mode of treatment has a wide variety of applications in the art, and while we do not claim the same as a means for treating or curing any particular ailments or diseases, we will state that eminently satisfactory and remarkable results have been achieved in a variety of cases. In the case of fibrous growths, whether benign or malignant, the fibrous cells seem to be definitely disorganized, without any interruption, and, in fact, with a definite stimulation, of the circulatory systems feeding the same, with the result that marked shrinkages of such growths have been noted. Furthermore, it has been definitely ascertained that malignancy ceases in the areas that have been subjected to the treatment, thereby confirming our conclusion that the cell activities have become disorganized.

Similar desirable results have been achieved in the alleviation of prostate gland enlargements or swellings, in connection with shrinkage of tonsils and the like, in the treatment of various rectal troubles, and in hypertrophies and protrusions in general, or any neoplasm, wherever situated.

Whatever the purpose of the treatment may be, it is apparent to us that an entirely new technique has been developed with far-reaching possibilities; and the essential characteristic of

the treatment, without regard to the particular tissue which is sought to be shrunk, or to the particular purposes for which such shrinkage may be sought, lies in heat treating the tissue, 5 by the passage of a high-frequency current of critical concentration, to a degree sufficient to devitalize tissue cells yet insufficient to impair the normal blood and lymph circulatory systems of the tissue.

10 It will be obvious that changes in the details herein described and illustrated for the purpose of explaining the nature of our invention may be made by those skilled in the art without departing from the spirit and scope of the invention as 15 expressed in the appended claims. It is therefore intended that these details be interpreted as illustrative, and not in a limiting sense.

Having thus described our invention, and illustrated its use, what we claim as new and 20 desire to secure by Letters Patent is—

1. The herein-described method of shrinking living tissue, which consists in heating the same to a degree sufficient to devitalize the tissue cells but insufficient to impair the liquid state of the 25 blood and lymph, whereby the blood and lymph flow are stimulated and the devitalized cells may be promptly absorbed.

2. The herein-described method of shrinking living tissue, which consists in passing there- 30 through a high-frequency electric current whose concentration is just sufficient to effect devitalization of the tissue cells but insufficient to coagulate the blood and lymph, whereby the devitalized cells may be promptly absorbed.

3. The herein-described method of shrinking living tissue, which consists in passing there- 35 through a high-frequency electric current whose concentration is within the range of approximately two to six milli-amperes per square millimeter, such concentration being sufficient to devitalize tissue cells but insufficient to impair the liquid state of blood and lymph.

4. The herein-described method of shrinking living tissue, which consists in passing there- 40 through a high-frequency electric current whose concentration is approximately four milli-amperes per square millimeter.

5. In an instrument of the character described, 45 a tubular electrode member having a rounded and closed forward tip composed of insulating material, a wall portion just rearwardly of the tip being of conductive material and adapted to serve as an operative surface for contacting tissue to be treated, the opposite wall portion being 50 cut away to provide a relatively large opening,

a laterally fenestrated endoscopic sheath enclosing said member, a telescope secured to said sheath and arranged within the electrode member to command a field of vision through said sheath fenestra, and means for rotating the electrode member relative to said sheath to selectively position the operative surface or the opposite opening in registry with said fenestra. 5

6. In an instrument of the character described, 10 a tubular electrode member having a rounded and closed forward tip composed of insulating material, a wall portion just rearwardly of the tip being of conductive material and adapted to serve as an operative surface for contacting tissue to be treated, said wall portion having a relatively small slit therein and the opposite wall portion being cut away to provide a relatively large opening, a laterally fenestrated endoscopic sheath enclosing said member, a telescope secured to said sheath and arranged within the 15 electrode member to command a field of vision through said sheath fenestra, and means for rotating the electrode member relative to said sheath to selectively position the operative surface or the opposite opening in registry with 20 said fenestra.

7. In an instrument of the character described, 25 a tubular electrode member composed of conductive material and having a forward wall portion adapted to serve as an operative surface for contacting tissue to be treated, the opposite wall being cut away to provide a relatively large opening, a telescope mounted within said member and adapted to command a forwardly oblique field of vision, and means for rotating the member relative to the telescope to bring either the operative surface or the opposite opening into 35 registry with the field of vision.

8. In an instrument of the character described, 40 a laterally fenestrated endoscopic tube of insulating material, a tubular metallic electrode member snugly yet rotatably mounted therein and provided with an apertured operative wall portion adapted to be rotated into registry with said fenestra, an electric terminal at the rear end of 45 said electrode member and adapted to be connected to a source of high-frequency current, and a telescope secured to said endoscopic tube and extending into the tubular electrode member so as to command an obliquely forward field of 50 vision through said fenestra and hence through the aperture in said operative wall portion when the latter is in registry with said fenestra.

REINHOLD H. WAPPLER.

FREDERICK CHARLES WAPPLER. 55
